UNITED STATES PATENT OFFICE.

CHARLES E. MILLER, OF CHICAGO, ILLINOIS, ASSIGNOR TO UNIVERSAL ARCH COMPANY, OF CHICAGO, ILLINOIS, A CORPORATION OF ILLINOIS.

ARCH-BRICK.

1,320,082.

Specification of Letters Patent.

Patented Oct. 28, 1919.

Application filed April 14, 1919. Serial No. 289,955

To all whom it may concern:

Be it known that I, CHARLES E. MILLER, a citizen of the United States, and resident of Chicago, in the county of Cook and State of Illinois, have invented certain new and useful Improvements in Arch-Brick, of which the following is a specification.

My invention relates to walls or baffles for furnaces and particularly to a novel brick construction adapted for use in a vertical baffle wall primarily intended for use in locomotives.

One of the objects of my invention is to provide a brick construction adapted to interlock with a duplicate brick in order to form a wall the elements of which are interlocked against lateral separation. The desired result is secured by constructing bricks of generally T-shape in plan view, the abutting edges of adjacent bricks being diagonally disposed with relation to the transverse axis of the wall, the taper of the sides of the brick at both the small and the large ends being in the same direction, that is, the sides of the small end of the brick converge toward the body and the sides of the large end converge toward a point away from the body. In walls of the character under consideration a series of air ducts are provided, these ducts in the present case being constituted by metal tubes rigidly held at their upper and lower extremities and serving to assist in retaining the bricks in place. The bricks are of duplicate construction and when alternate bricks are turned 180° and placed in end-to-end relation a tube is accommodated in the space at the ends of the mating bricks and they are securely held in place against movement in one direction by the interlocking effect and in another direction by engagement with a tube.

The invention will be more readily understood by reference to the accompanying drawings, wherein:

Figure 1 is a horizontal sectional view of a wall constructed in accordance with my invention, the bricks composing the wall being shown in plan view.

Fig. 2 is a vertical sectional view on the line 2—2 of Fig. 1; and

Fig. 3 is a sectional view through one of the bricks.

It will be understood that a wall such as contemplated by me is intended for use in locomotives and is known as the Gaines type.

In this construction air is admitted through the bottom of the fire box and delivered by means of tubes or passages to the furnace at a point above the fuel bed. In view of the tremendous strain and wear to which such walls are subjected it has been found difficult to maintain them for any considerable length of time. By reason of my arrangement the bricks composing the wall have greater stability and cannot readily become displaced.

The wall is composed of a plurality of whole bricks 10 and half bricks 11, a number being employed sufficient to bridge the space between the side sheets 9 of the boiler. Air is supplied to the fire box by means of tubes 12, or similar passage ways, the tubes being bent at right angles at their upper ends as shown in Fig. 2, in order to discharge the air at a point above the fuel bed and anchored in a top course of bricks. The bricks composing the wall serve a double purpose of providing a baffle and protecting the air supplying tubes. To that end the bricks are formed of generally T-shape in plan view, the construction being such that when two duplicate bricks are placed end to end a space 13 is left for a tube 12. The engaging surfaces of both the small and large ends of the brick are tapered, the taper 14 of the small end corresponding to the taper 15 of the large end. The inclines are such that when the bricks are associated as shown in Fig. 1, and the ends are held as by abutment against the side sheet of the boiler, the bricks cannot be moved laterally but are interlocked and can only be separated by movement vertically. This result is secured by tapering both the small and the large ends of the brick and by coöperation with the tubes 12. Because of the tapered ends alternate bricks are prevented from movement in opposite directions away from each other. They are prevented from movement in the opposite directions by contact first with the tubes, and, second in the absence of the tubes with the large end of the mating bricks. It is understood, of course, that it is necessary in order to secure the effect described, to firmly hold the end bricks in order that the bricks may not separate longitudinally of the wall.

The end bricks 11 are usually formed with flat ends in order to properly coöperate with the side sheet, the end adapted to coöperate

with a full size brick being the same as that heretofore described. The bricks will preferably be lightened by providing recesses 16 in one surface thereof and this practice will 5 also be followed in the half bricks 11, in which case a half recess 17 will be formed.

Obviously the exact form of the bricks may be varied somewhat without departure from the spirit of my invention and I do 10 not wish to be limited except as indicated by the appended claims.

I claim:

1. In a vertical wall construction for fire boxes, the combination of a plurality of 15 bricks adapted to be placed in end to end relation and to provide a vertical passage at their junction, said bricks being generally T-shaped in plan view, the abutting surfaces of adjacent bricks being angularly disposed 20 with relation to the transverse axis of the wall, and adjacent bricks being positioned to overlap and interlock, and means for retaining the bricks against longitudinal separation, substantially as described.
- 25 2. A vertical baffle-wall brick of T-shape in plan view, the side edges of the head being adapted to coöperate with the side edges of the foot of a duplicate brick in order to hold the bricks against lateral separation in one 30 direction, both the head and foot being wedge-shaped in plan view, a plurality of

said bricks being adapted to be associated in end to end relation and to be held in interlocked position, substantially as described.

3. A vertical baffle-wall brick of T-shape 35 in plan view, the sides between the head and foot being recessed to provide for a duct, the head and foot portions being wedge-shaped in plan view, the sides of the foot portion converging toward the head and the sides of 40 the head having the same inclination, a plurality of said bricks being adapted to be associated in end to end relation and to be held in interlocked position, substantially as described. 45

4. In a vertical baffle-wall, the combination of bricks of T-shape in plan view, providing a vertical passage at the junction of adjacent bricks, and a tube in said passage, the two ends of said bricks being wedge-shaped 50 in plan view, mating bricks being interlocked against lateral movement in one direction by reason of said wedge-shaped ends and held against movement in the opposite direction by engagement with said tube, 55 substantially as described.

Signed at Chicago, this 11th day of April, 1919.

CHARLES E. MILLER.
